UNITED STATES PATENT OFFICE.

PEDRO ROTH AND MÁXIMO EDUARDO VENTURINO, OF BUENOS AIRES, ARGENTINA.

PROCESS FOR THE CONVERSION OF HEAVY PRODUCTS OF PETROLEUM.

1,208,378.

Specification of Letters Patent. Patented Dec. 12, 1916.

Application filed October 16, 1916. Serial No. 126,057.

To all whom it may concern:

Be it known that we, PEDRO ROTH and MÁXIMO EDUARDO VENTURINO, citizens of the Argentine Republic, residing at No. 750 5 Moreno street, Buenos Aires, Argentina, have invented certain new and useful Improvements in Processes for the Conversion of Heavy Products of Petroleum, of which the following is a specification.

- 10 The present invention relates to the conversion or transformation of the heavy products of petroleum into lighter products, or products of less density, and has for object a process by means of which the heavy products of petroleum, such as the hydrocarbons which form kerosene, gas oil, lubricating oils and paraffin, are converted into other lighter products, such as gases and petroleum ether, gasoline, naphtha and benzin.
- 15 For brevity in the description and in order to facilitate the general understanding of this specification, the general term "heavy products of petroleum" should be interpreted as comprising kerosene and all 20 heavier hydrocarbons, while under the denomination "lighter products of petroleum," are comprised benzin, naphtha, gasoline, petroleum ether and gases.

25 By means of the process which forms the subject of this invention, it will therefore be possible to convert or transform all kinds of crude petroleum, mixtures of by-products of petroleum with crude petroleum, gas oil, etc., into petroleum ether or gases, gasolines, naphtha, benzin, residues and coke, and it will also be possible to completely eliminate, if so desired, the kerosenes and oils which as a result of the known processes, represent 30 the larger percentage of the products obtained by the distillation of natural petroleum.

The process which forms the subject matter of the present invention, consists in causing said heavy hydrocarbons to fall either 45 in a liquid state or pulverized, upon a mass of residues of petroleum, asphalt or oils, heated to a temperature higher than the boiling point of the hydrocarbons to be converted and thereupon to condense the vapors generated at the contact of said atomized hydrocarbons with said heated mass.

50 Instead of employing crude residues of petroleum or asphalt to produce cracking, crude petroleum may be used and is first 55 partially distilled and heated to a temperature high enough to cause a cracking on the

incoming crude petroleum which is sprayed into the vapor space of the still or boiler and comes in contact with the heated mass.

In the drawing which accompanies this 60 specification, a diagram of an apparatus for carrying the invention into practice, is shown, although it will be understood that any other suitable apparatus might be used for the purpose.

65 A boiler 1, mounted on a body of masonry, is heated in any suitable manner by means of a fire box 2 arranged below the same. For the heating of said fire box, oil or gas burners may be arranged, or systems using 70 solid fuel, or any other heat-generating means may be employed. Near the top, the boiler is provided with one or more discharge goosenecks or exits 7 for the escape 75 of the vapors of distillation generated inside the boiler. In order that the bottom of the boiler may be cleaned when so desired, one or more openings 8, provided with closing appliances, are arranged, though same are not shown in the drawings. Through an 80 inlet pipe, also not represented in the drawings and which may be inserted at any convenient point, the residues of petroleum, asphalts or oil are fed into the boiler or still 85 1, and heated to a temperature above the boiling point of the heavy products of petroleum which are to be converted or transformed. The boiler is preferably filled to slightly less than half its capacity. The middle or heavy by-products of petroleum 90 such as oils, paraffins, lubricating oils, gas oil or kerosene, are introduced into the boiler by means of a tube 4, communicating with any suitable reservoir, not shown, from which the petroleum passes by said tube to 95 a compressor or pump 5, of any suitable type, in order to be finally discharged into said boiler by an atomizer 6 which may also be of any desired construction.

100 The goosenecks or exits 7 communicate with a condensing coil, not represented in the drawing, by means of which we condense the vapors generated in the interior of the boiler on the contact of the heavy by-products of petroleum, in atomized condition, with the heated mass 3. The level of the mass in the boiler should remain more or less unchanged owing to the fact that the temperatures employed is generally lower than the boiling point of the said mass 3. 110

The different experiments heretofore carried out, have shown that a slight lowering

2
of the temperature of the mass 3 during the converting operation increases the percentage of kerosene in the converted product, which fact is of some importance when a 5 more or less considerable proportion of said hydrocarbon is to be obtained. From what has been stated it will be evident that the division between the heavy products of petroleum and the lighter products of the 10 same, according to meaning given to said denominations in conformity with this invention, is not an absolute division, but a relative and variable one; thus, for instance, kerosene may be regarded as being a light 15 product when in the converted final product a smaller or larger proportion of this hydrocarbon is desired.

We declare that what we claim as new and desire to secure by Letters Patent, is:—

20 1. The process for converting the heavy or middle distillates of petroleum into lighter products of the same, consisting in heating a mass of residues of petroleum, asphalt, or oils, to a temperature above the boiling 25 point of the hydro-carbons, which it is desired to crack, and then introducing undiluted petroleum distillates into the still in the form of a spray upon the mass of residues of petroleum, asphalt, or oils, through 30 the vapor space of the still, and through an unobstructed passage to said liquid mass,

wherby a portion of such sprayed petroleum is vaporized before coming in contact with the liquid mass in the still and the greater proportion of the volatilizing and 35 cracking of the sprayed distillates occurs on contacting with the liquid mass, and thereupon condensing the vapors generated.

2. The method of destructive distillation of crude petroleum, consisting in heating a 40 body or mass of crude petroleum in a boiler or still to a temperature to produce cracking thereby vaporizing a considerable proportion of the lighter ingredients thereof and leaving a residue containing the heavier 45 portions thereof, and then introducing undiluted crude petroleum in the form of a spray through the vapor space of the still upon the mass of crude petroleum, and through an unobstructed passage to said 50 liquid mass, wherby a portion of such sprayed petroleum is vaporized before coming in contact with the liquid mass in the still, and the greater proportion of the volatilizing and cracking of the sprayed petroleum 55 occurs on contacting with the liquid mass.

In testimony whereof we affix our signatures.

PEDRO ROTH.
MÁXIMO EDUARDO VENTURINO.
